Hasegawa et al.

[11] Patent Number: Des. 319,629

[45] Date of Patent: ** Sep. 3, 1991

[54] SEMICONDUCTOR SUBSTRATE WITH CONDUCTING PATTERN

[75] Inventors: Terutomi Hasegawa, Ogaki; Nobumichi Goto, Seki, both of Japan

[73] Assignee: Ibiden Co., Ltd., Ogaki, Japan

[*] Notice: The portion of the term of this patent subsequent to Jul. 23, 2005 has been disclaimed.

[**] Term: 14 Years

[21] Appl. No.: 181,253

[22] Filed: Apr. 13, 1988

[52] U.S. Cl. D13/182

[57] CLAIM

The ornamental design for a semiconductor substrate with conducting pattern, as shown.

DESCRIPTION

FIG. 1 is a top perspective view of a semi-conductor mounting device showing our new design;

FIG. 2 is a bottom perspective view thereof;

FIG. 3 is a right side elevational view thereof;

FIG. 4 is a left side elevational view thereof;

FIG. 5 is a rear elevational view thereof; and

FIG. 6 is a front elevational view thereof;

FIG. 7 is a top plan view thereof; and

FIG. 8 is a bottom plan view thereof.
